No. 651,449.

Patented June 12, 1900.

H. A. SCHERMERHORN.

DOOR FOR GRAIN OR FREIGHT CARS.

(Application filed Mar. 26, 1900.)

(No Model.)

UNITED STATES PATENT OFFICE.

HERSCHEL A. SCHERMERHORN, OF WATERMAN, ILLINOIS, ASSIGNOR OF
ONE-HALF TO JAMES A. POTTER, OF SHABBONA, ILLINOIS.

DOOR FOR GRAIN OR FREIGHT CARS.

SPECIFICATION forming part of Letters Patent No. 651,449, dated June 12, 1900.

Application filed March 28, 1900. Serial No. 10,176. (No model.)

To all whom it may concern:

Be it known that I, HERSCHEL A. SCHERMERHORN, a citizen of the United States, residing at Waterman, in the county of De 5 Kalb and State of Illinois, have invented certain new and useful Improvements in Doors for Grain or Freight Cars, of which the following is a specification.

This invention relates to improvements in 10 the construction and means for operating the inner doors of grain or freight cars in which the grain is shipped in bulk or in loose form; and it consists in certain peculiarities of the construction, novel arrangement, and operation 15 of the various parts thereof, as will be hereinafter more fully set forth and specifically claimed.

The objects of my invention are to provide 20 a door for grain-cars or receptacles employed for similar purposes which shall be simple and inexpensive in construction, strong and durable, and which on account of the peculiar and novel means employed may be easily raised and lowered, so as to allow the grain 25 to be removed from the car or other receptacle or to be placed therein in the most convenient and efficient manner without the use of crow-bars or other prying instruments which are generally used to open or raise the doors for 30 grain-cars now ordinarily in use.

Another object is to provide means for retaining the door in its raised position, so that it can be readily released and lowered automatically or by its own gravity.

Still another object is to so construct the 35 tracks or guideways for the pulleys as to prevent grain accumulating therein, so as to block or impede their progress in the raising or lowering of the door.

Other objects and advantages will appear 40 in the subjoined description and explanation.

In order to enable others skilled in the art to which my invention pertains to make and use the same, I will now proceed to describe 45 it, referring to the accompanying drawings, in which—

Figure 1 is a view, partly in section and partly in elevation, of a portion of a grain or freight car with my invention applied thereto 50 and showing the parts thereof as viewed from within the car. Fig. 2 is a cross-sectional

view of a fragment of the car, showing the door in its lowered position by continuous lines and in raised position by broken lines. Fig. 3 is an enlarged view, in side elevation, 55 of the lifting and lowering mechanism for the door detached. Fig. 4 is an edge view of a portion of the said mechanism; and Fig. 5 is a plan sectional view, partly in elevation, taken on line 5 5 of Fig. 1, showing a portion 60 of the door and one of its bracketed rollers and one of the grooved standards or uprights.

Similar letters refer to like parts throughout the different views of the drawings.

A represents a grain-car, which may be of 65 the ordinary or any preferred construction, or it may represent any other kind of receptacle, such as a garner or granary. This receptacle is formed with a doorway B, which usually extends from the bottom of the car 70 to about its top, as is clearly shown in Fig. 1 of the drawings. Located at each side of the doorway B is a grooved way C, which in the present instance I have shown as being formed of a standard or upright having a groove c on 75 its outer surface; but said ways may be otherwise made, as is obvious. Secured to the bottom A' of the car or receptacle A, on each side to the doorway, is a rod or bar D, which extends upwardly in the groove c of the guideways C to near the top of the doorway and is then curved inwardly and secured at its other end to a joist d at about the middle of the car or receptacle, as is shown in Fig. 2 of the drawings. Located between the rods or bars 80 D and resting against the inner surfaces of the guideways C is a door E, which preferably has secured to its upper portion, by means of hinges e, a leaf or extension E', which may be folded to the position indicated 85 in dotted lines in Fig. 2 of the drawings or may be raised when the car is sufficiently filled with grain to the position shown by full lines in Fig. 1 of the drawings. Secured to the door E at each of its edges are brackets 90 e' and e'', which project from the edges of the door and are formed into loops substantially rectangular in shape, which loops embrace the rods D and hold the door in a vertical position. Each of these looped brackets is provided with a grooved pulley e'', which travels 95 on the outer surface of the rods or bars B and 100

within the grooves *e* of the guideways *C* at the sides of the doorway.

By reference to Figs. 1, 2, and 3 of the drawings it will be seen and clearly understood that the loops of the brackets *e'* are inclined downwardly and extend into the grooves *c* of the guideways, while the brackets *e''* are inclined upwardly and also extend into said grooves. This arrangement of the brackets is employed to prevent binding when the door is raised and carried along the curved portions of the rods *D*, which act as rails or tracks for the pulleys on said brackets. Secured to the upper portion of the car or receptacle and usually to one of the cross-beams *d'* is a bracket *F*, in the lower portion of which is journaled a grooved pulley *f*, over which passes a chain *g*, the lower end of which is secured to the lower portion of the door *E* at about the middle thereof. To the free end of the chain *g* is fulcrumed a lever *G*, one end of which is provided with prongs *g'* to stride the chain *g* and to engage the same, as will be presently explained.

Pivotal secured on the bracket *F*, just above the pulley *f*, is a catch *h*, which has three prongs *h'* (see Fig. 4 of the drawings) to engage the links of the chain. This catch is provided with an extension or arm *h''* to hold the hooks or prongs *h'* in contact with the chain.

When the door is in its lowered position, the lever *G* will be suspended somewhat above the door, as shown in Fig. 1, and when it is desired to raise the door the forked end of the lever may be placed astride the chain, when by bearing down on the longer portion of the lever the door will be raised slightly, when the prongs may be disengaged from the chain and a new hold thereon taken and the door again lifted, and so on, until it reaches the desired height or its uppermost position, as shown by dotted lines in Fig. 2 of the drawings, in which position, as well as the position when new holds are being taken with the lever, it will be held by reason of the catch *h* engaging the links of the chain, thus preventing it slipping backwardly. The catch *h* being formed with three prongs it is apparent that the outer ones will guide the chain so as to cause the inner prongs to be inserted in one of the links. When it is desired to lower the door, the catch *h* may be lifted out of engagement with the chain, when the door will be lowered by reason of its gravity and will be guided to its proper position through the medium of the bracketed rollers and

guide rods or bars. The lower portions of the guideways *C* are cut away, as at *c'*, to allow the grain which might accumulate in the groove or channel of the guideway to pass out into the car, thus preventing the guideway becoming clogged.

Having thus fully described my invention, what I claim as new, and desire to secure by Letters Patent, is—

1. The combination with a car or receptacle having a doorway, of a rod or bar secured to the floor thereof and extending upwardly and inwardly near each side of the doorway, a door having near the lower portion of each of its ends, a bracket with downwardly and outwardly-extending loops, and near the upper portion of each of its ends upper and outwardly-extending loops, all of said loops embracing the said rods or bars, a pulley on each of said loops, and means to lift the door, substantially as described.

2. The combination with a car or receptacle having a doorway, of a rod or bar secured to the floor thereof and extending upwardly and inwardly near each side of the doorway, a door having near the lower portion of each of its ends, a bracket with downwardly and outwardly-extending loops, and near the upper portion of each of its ends upper and outwardly-extending loops, all of said loops embracing the said rods or bars, a pulley on each of said loops, a pulley journaled above the door, a chain secured at one of its ends to the door and passing over said pulley, a lever fulcrumed at the other end of said chain and having a forked end, and a catch pivotally secured near the said pulley to engage the chain, substantially as described.

3. The combination with a car or receptacle having a doorway, of a vertically-grooved way located at each side of the doorway and having its lower portion cut away, a rod or bar secured to the floor of the car and extending upwardly in each of said ways and then inwardly, a door having near the lower portion of each of its ends a bracket with downwardly and outwardly-extending loops, and near the upper portion of each of its ends, upper and outwardly-extending loops, all of said loops embracing said rods or bars, a pulley on each of said loops, and means to lift the door, substantially as described.

HERSCHEL A. SCHERMERHORN.
